UNITED STATES PATENT OFFICE.

EDWARD W. STEVENS, OF DETROIT, MICHIGAN, ASSIGNOR TO CHICAGO PNEUMATIC TOOL COMPANY, OF NEW YORK, N. Y., A CORPORATION OF NEW JERSEY.

SHAFT PACKING.

Original application filed March 17, 1925, Serial No. 16,095. Divided and this application filed March 19, 1926. Serial No. 95,842.

The present invention relates to packings generally, and more particularly to improved packings for reciprocating stems, rods and shafts. This application is a division of my 5 copending application, Serial No. 16,095 filed March 17, 1925.

Among the objects of the invention are to facilitate the handling and insertion of packings, to provide a new form of molded packings and protective container or package therefor, and in general to improve prior forms and methods.

In order to illustrate the invention and the manner of its use one concrete embodiment 15 thereof is shown in the accompanying drawings in which:

Fig. 1 is a longitudinal sectional view through the forward end of the cylinder of a pneumatic sand rammer;

20 Fig. 2 is a right end elevation of the part shown in Fig. 1.

Fig. 3 is a view similar to Fig. 1 on a reduced scale showing the manner of inserting a new packing, and

25 Fig. 4 is a perspective view of the molded packing in its container.

The embodiment of the invention chosen for the purpose of illustration is shown in the drawings as sealing the forward end of the 30 piston chamber of a pneumatic sand rammer comprising the cylinder or barrel 5 in which piston 6 reciprocates, the latter having attached thereto or integral therewith a stem 6^a which projects beyond the cylinder 5 and 35 carries the butt or pein (not shown). The motive fluid admitted to the front end of the piston chamber through passage 7 to drive piston 6 on its back stroke is sealed against escape through the forward open end of the 40 cylinder by the following construction. A packing gland member 8 in the form of a hollow cylinder or sleeve is rigidly secured within the open end of the cylinder as shown. One method of rigidly securing member 8 in the 45 cylinder is to provide the latter with internal screw threads 5^a and the member with external screw threads 8^a. Opposite slots as 8^b permit the use of a spanner wrench for inserting member 8 and a shoulder 8^c cooperat- 50 ing with a similar shoulder within cylinder 5 serves as a stop. The cylinder bore 9 of member 9 receives stem 6^a with a sliding fit and serves as a bearing for the latter. Member 8 is provided with counter bore 9^a in which

packing material 10 is seated surrounding 55 stem 6^a and a second gland member 11 in the form of a cylinder sleeved over stem 6^a makes a close sliding fit with counterbore 9^a and telescopes within member 8 to place packing 10 under compression. Member 11 is of sub- 60stantial length as indicated and projects beyond cylinder 5. A gland nut 12 having a head 12^a with a bore 12^b loosely receiving stem 6^a is provided with a cylindrical extension 12^c arranged loosely to telescope over the 65 projecting portion of member 11 and is exteriorly threaded for engagement with the interior threads 5^a of cylinder 5. Head 12^a is formed with a rim extending beyond cylinder portion 12^c and interposed between this 70 rim and the end of the cylinder 5 and surrounding projection 12^c is a coiled spring 13 whose ends 13^a and 13^b are removably seated in sockets 5^b and 12^d respectively in cylinder 5 and nut head 12^a to hold the manually ad- 75 justable nut 12 in adjusted position.

Fig. 4 illustrates the manner in which packing material 10 is arranged for insertion in the above recited gland. As indicated the material is molded to the proper size and 80 shape and enclosed in a cylindrical holder, container or envelope 14 of any suitable material, such as cardboard. The manner of inserting the packing is clearly indicated in Fig. 3. With gland member 8 in position as 85 shown the molded packing 10 in its container as a unit is sleeved over the piston stem 6^a until the container 14 abuts the outer end of member 8. Gland member 11 is then sleeved over the stem 6^a and is telescoped within the 90 container 14 forcing the molded packing 10 into the counterbore 9^a of gland member 8, the member 11 being forced through packing 10 and into telescoping engagement with member 8 until the parts reach the position 95 shown in Fig. 1, the packing then being seated in its recess. The container or envelope 14 is now removed from the stem 6^a and the gland nut 12 with its locking spring is applied and set up to put packing 10 under the 100 desired compression. The tool is then ready for use.

From the above it will be apparent that the present invention provides an improved package for merchandising molded packings 105 and for protecting the same at all times. In its package the packing is maintained in shape until actually placed in the packing

recess; in fact the packing is not removed from its container until it is forced therefrom directly into the packing recess, the container thus acting as a guide to facilitate the accurate insertion of the packing.

While the preferred form of the invention has been herein shown and described the invention is not limited to the specific details thereof but covers all changes, modifications and adaptations within the scope of the appended claims.

I claim as my invention:

1. A packing for reciprocating stems, rods and shafts, comprising packing material molded into the required shape and size, and

a cylindrical container therefor having the double function of a protecting package for the packing and of means for disposing the packing to be forced therefrom directly into the packing recess.

2. As a new article of manufacture, a stiff hollow cylinder and a packing molded of relatively soft material within said cylinder and retained in shape thereby and arranged to be forced therefrom directly into a packing recess.

Signed by me at Detroit, Michigan, this 16th day of March, 1926.

EDWARD W. STEVENS.
